UNITED STATES PATENT OFFICE

118,550

DESIGN FOR A COMBINED LAMP, RADIO, AND CLOCK

Theodore Tinker, Norwalk, Conn., and George
von der Lin, Jackson Heights, N. Y.

Application May 9, 1939, Serial No. 84,894

Term of patent 7 years

To all whom it may concern:

Be it known that we, Theodore Tinker and George von der Lin, citizens of the United States of America, residing at Norwalk, in the county of Fairfield and State of Connecticut, and Jackson Heights, in the county of Queens and State of New York, respectively, have invented a new, original, and ornamental Design for a Combined Lamp, Radio, and Clock, of which the following is a specification, reference being had to the accompanying drawing, forming a part thereof.

In the drawing, the figure is a perspective view

of a combined lamp, radio, and clock, showing our new design.

The opposite side of the clock casing is of plain hemispherical form and the opposite side of the base member is plain and devoid of surface projections. The salient features of the design are shown in full lines in the drawing.

We claim:

The ornamental design for a combined lamp, radio, and clock, as shown and described.

THEODORE TINKER.
GEORGE VON DER LIN.
